HIS ATTORNEY'S:

UNITED STATES PATENT OFFICE.

LIAM JAMES STEWART, OF GLASGOW, SCOTLAND, ASSIGNOR OF ONE-HALF TO MARY ANNE STEWART, OF ARDMORE, SCOTLAND.

APPLIANCE FOR WORKING TRAMWAY OR RAILWAY POINTS.

SPECIFICATION forming part of Letters Patent No. 680,007, dated August 6, 1901.

Application filed April 16, 1901. Serial No. 56,135. (No model.)

To whom it may concern:

Be it known that I, WILLIAM JAMES STEWART, commission merchant, a subject of the King of Great Britain and Ireland, and a resident of 82 Virginia street, Glasgow, Scotland, have invented certain new and useful Improvements in Appliances for Working Tramway or Railway Points, (for which I have made application for a patent in Great Britain, No. 16,667, bearing date the 19th of September, 1900,) of which the following is a specification.

My invention relates to improvements in appliances for working tramway or railway points, and has for its object the enabling of such points to be shifted or actuated from the car or other vehicle by the driver or conductor in a simple and efficient manner without having to stop the vehicle.

Referring to the drawings which form a part of this specification, Figure 1 is an elevation of a tramway-rail, partly in section. Fig. 2 is a plan showing the arrangement of the rails and points. Fig. 3 is a plan, to an enlarged scale, illustrating the point-shifting mechanism. Fig. 4 is a longitudinal section of the lower part of a vehicle, illustrating the arrangement of the appliances for actuating the points; while Fig. 5 is a plan of a detail.

In carrying into practice the improvements of my invention the rails *a*, carrying the points *b*, are formed with their grooves *c* gradually sloping to a level deeper than usual, as shown in Fig. 1, at the part where the point-tongue *b* is situated and a little in advance of same, so that the ordinary car-wheels may pass over without touching the shifting devices, and gradually sloping upward again till slightly above the ordinary level, as at *d*,

where it falls again to the ordinary level beyond the point. As illustrated more particularly by Fig. 3, a narrow wedge-shaped tongue-piece *e* is pivoted by its narrow end to oscillate through a slot or in a recess *f*, formed in the inner side of the rail *a*, with its broad end or base *e'* in its acting position lying across the groove *c*. This tongue-piece *e* is jointed at *b'* to the free end of the movable tongue *b* of the point, which is made deep enough to rest on the bottom of the groove *c*.

Fitted in this way the tongue-piece *e* when pushed to one side will carry the point *b* with it. Another tongue-piece is similarly fitted on the opposite rail when two movable points are fitted opposite each other, and the two movable tongues *b b* are connected by the rod *g*, jointed to both. Covering-plates *h* and *i*, which may be in two parts and hinged, as shown, to lift up, or may be loose, are used to cover the tongue-pieces *e*, and these are shown on one rail as opened up and on the other as closed. A casing *j* incloses and covers the connecting-rod *g*.

As illustrated by Fig. 4, horizontal levers *k* are mounted under the car-body *l*, having their inner ends fulcrumed on brackets *m*, preferably mounted on the axles *n*, or it may be on any other portion of the car. Vertical rods *o*, depending from these levers *k* through guides *p*, carry narrow pulleys or wheels at their lower ends, which run in the grooves *c* of the rails *a*. The outer ends of the levers *k* may, if desired, be weighted or fitted with reaction-springs (not shown in the drawings) and are jointed to vertical rods *r*, passing up through the floors of the drivers' platforms *s* and guides *s'* on same, where they are held in their higher or non-acting position by ratchets *t*, formed with any desired number of teeth and pawls *u* or other like devices to be operated either by hand or foot. A toe or projection *v* is formed on the lower end of each rod *o* for the purpose of actuating the tongue-piece *e* and clearing the rail-groove, and wings *w* are formed above the toe for the purpose of throwing dirt or the like to each side of the rail, these wings being shown in the detail plan, Fig. 6. These actuating-toes, with wheels and levers, as described, may be fitted at one or both sides of the car and at one or both ends and may be worked from any part of the car by suitable appliances.

When it is desired to shift a point, on approaching same the driver releases the lever *k* from its connection with the ratchet *t* and allows the rod *o* to descend, which causes the wheel *q* to descend into the depressed part of the groove *c* and the rod *o* or the toe *v* thereon to come into contact with the tongue-piece *e* to push it to one side, which action

carries over the point-tongue *b* along with it. When the wheel passes the point, it ascends the grooves *c* to the point *d* slightly above the ordinary level and at the same time 5 pushes up the lever *k* and vertical rod *r* and locks it in position by the action of the pawl *u* and ratchet *t*.

Holes may be formed, as indicated at *x* in Fig. 2, leading from the groove *c* of the rails *a* 10 to a drain below to allow water to escape, and openings may be formed, as indicated at *y* in Fig. 1, through the sides of the rails to allow the point-tongue *b* when moved to force any mud or fluid matter through these openings 15 into a box below, (indicated in dotted lines,) whence it can be periodically removed. Arched openings (indicated at *z* in Fig. 1) may be formed through the point-tongue *b* to enable it to move easily, though some mud may 20 be deposited in the groove.

Having now described my invention, what I claim as new, and desire to secure by Letters Patent, is—

1. In appliances for working tramway or 25 railway points the combination with rails having specially-deepened grooves, and fitted with shifting tongue-pieces jointed to the point-tongues and connected by a tie-rod, of actuating-rods with wheels on the vehicles 30 suspended by rods from horizontal levers carried by vertical rods *t* held out of acting position by a ratchet and pawls substantially as set forth.

2. In appliances for working tramway or 35 railway points the combination comprising the rail *a* having a specially-deepened groove *c*, the tongue-piece *e* jointed to the point-tongue *b* and the toe-piece *v*, wheels *q*, rod *o* lever *k*, rod *r* with ratchet-and-pawl mechan-

ism on the vehicle-body substantially as set forth.

3. In appliances for working tramway or railway points the combination with shifting tongue-pieces jointed to the point-tongues, of the toe-piece *v*, with wheel *q*, the rod *o*, the 45 lever *k* and the rod *r* fitted with ratchet-and-pawl mechanism substantially as set forth.

4. In appliances for working tramway or railway points, a rail having a deepened groove and a raised portion *d* in the groove, 50 a point *b* and a tongue-piece attached thereto, said tongue-piece extending within the groove but a distance below the top of rail, in combination with a car, a wheel on the car adapted to travel in the groove and carrying means to move the tongue-piece and ratchet-and-pawl means to hold the wheel out of operative position upon the wheel striking the raised portion *d* of the groove, substantially as described.

5. In appliances for tramway and railway points, a rail having a deepened groove and a raised portion *d* in the groove, a wheel carried by the car and adapted to run in the groove and levers on the car to lift or lower the wheel, in combination with a pawl-and-ratchet means secured to the levers to hold the wheel in its raised position upon its striking the raised portion of the groove *d*, substantially as described.

In testimony whereof I have signed my name to this specification in the presence of two subscribing witnesses.

WM. JAMES STEWART.

Witnesses:

R. C. THOMSON,
WM. RUTHERFORD.

It is hereby certified that the residence of the assignee in Letters Patent No. 680,007, granted August 6, 1901, upon the application of William James Stewart, of Glasgow, Scotland, for an improvement in "Appliances for Working Tramway or Railway Points," was erroneously written and printed "Ardmore, Scotland," whereas said residence should have been written and printed *Ardmore, Gourock, Scotland*; and that the said Letters Patent should be read with this correction therein that the same may conform to the record of the case in the Patent Office.

Signed, countersigned, and sealed this 24th day of December, A. D., 1901.

[SEAL.]

F. L. CAMPBELL,
Assistant Secretary of the Interior.

Countersigned:

F. I. ALLEN,
Commissioner of Patents.
